UNITED STATES PATENT OFFICE.

EUGENE FONTAINE, OF DETROIT, MICHIGAN, ASSIGNOR TO THE UNIQUE NOVELTY COMPANY, OF SAME PLACE.

SELF-HEATING CURLING-IRON.

SPECIFICATION forming part of Letters Patent No. 511,297, dated December 19, 1893.

Application filed February 27, 1893. Serial No. 463,880. (No model.)

To all whom it may concern:

Be it known that I, EUGENE FONTAINE, a citizen of the United States, residing at Detroit, in the county of Wayne and State of Michigan, have invented certain new and useful Improvements in Curling-Irons, of which the following is a specification, reference being had therein to the accompanying drawings.

This invention relates more particularly to that class of curling irons which are provided with means for heating the same, and my invention consists in the peculiar construction, and arrangement of the curling rod in connection with a self heating device, all as more fully hereinafter described and shown in the drawings, in which—

Figure 1 is an elevation of my improved curling iron. Fig. 2 is a central section with the hinged joint opened. Fig. 3 is a horizontal section on line x x , in Fig. 1.

A is the hollow handle inclosing a wick tube B which is closed at the bottom by a filling plug C and terminates on top in the burner D, all so arranged that a wick saturated with a suitable burning fluid may be lighted at the burner to produce a suitable flame for heating.

E is a bell shaped cap inclosing the burner. It is hinged at a to an annular flange F, formed around the burner and which fits into a corresponding recess formed in the base of the cap. A locking spring G is secured to the cap and is adapted to engage with the flange F and thereby lock the cap in position.

The cap E and flange F are provided with a number of apertures suitable to admit air to sustain the flame inside the cap when the wick is lighted and to form an escape for the products of combustion. Into the top of this cap is secured a solid curling rod H of copper or other metal forming a good conductor of heat. This rod extends through the cap into the interior thereof and forms to a greater or less extent an inner lining thereto. This I preferably accomplish in a simple manner by dividing the end of the rod into several parts I and inserting the rod far enough so that by peening over the divided ends, they line the

inner wall of the cap or rather a portion thereof, so as to leave enough space for the flame and gases of combustion to pass out. After peening over and flattening the ends out more or less they may be bent away from the wall of the cap so as to be out of contact with the metal of the cap. By this construction of the curling rod, the flame instead of heating the cap heats the ends of the rod and the heat which it thus receives is directly conducted through the whole length of the rod and makes it very effective as a curling iron, as the whole heat of the flame is expended on the curling iron, while the cap remains comparatively cool, at least enough to prevent injury to the hands from burning.

The curling iron is provided with the usual pivoted jaw L, which has a thumb piece M and a spring N adapted to normally close the jaw around the curling iron, the said jaw being of the usual semi-cylindrical shape to fit the curling rod.

What I claim as my invention is—

1. In a curling iron the combination with a reservoir handle, a burner on the end thereof, a perforated cap movably secured on the handle and extending over the burner, and a curling iron secured centrally in the cap its inner end entering the cap and separated longitudinally from a point directly over the burner, the respective members of the separated portion being curved outwardly to a point adjacent to the inner wall of the cap, and around the burner, substantially as described.

2. In a curling iron the combination with a handle having a burner thereon, a perforated cap over the burner, and a curling iron secured to the cap having its inner end split apart, flattened and flared outwardly in opposite directions around the burner, substantially as described.

In testimony whereof I affix my signature in presence of two witnesses.

EUGENE FONTAINE.
